UNITED STATES PATENT OFFICE

2,438,054

SADIRON HOLDER

Margaret May Holliday, Detroit, Mich.

Application September 29, 1945, Serial No. 619,375

2 Claims. (Cl. 248—117.1)

1

My invention relates to laundering and has for its object to provide means for suspending a sadiron from an ironing board.

Another object of this invention is to provide an adjustable holder for a sadiron.

A further object of my invention is to provide means supported by an ironing board for holding a hot iron.

Other features and advantages will become more readily apparent from the following description and the accompanying illustrative drawings in which:

Figure 1 is a perspective view of my invention.

Figure 2 is a broken away end of an ironing board embracing my iron holder.

Figure 3 is a similar view showing the holder in adjusted position, and

Figure 4 is a perspective view of an ironing board embracing my invention and illustrating its application.

In the above drawings as well as in the specification to follow, the same characters of reference indicate the same parts throughout.

In the accompanying drawings, 19 indicates my invention which consists of a short iron bracket 11 of U-shape and provided with horizontally disposed flanges 12 and 13 turned out from the upper ends 14 and 15 of its arms 16 and 17. The flanges are provided with bores 18 and 19 to receive the screw ends of bolts 20 and 21 (shown dotted) which project through the butt end 22 of an ironing board 23, the heads 24 of the bolts being countersunk in the upper face 25 of the board.

The said arms 16 and 17 are provided with oppositely disposed square openings 26 and 27, the lower ends of which are on a common plane with the inner surface 28 of the plate 29 of the member 11. Slidably mounted upon said plate and through said openings is a square rod 30 having a stop pin 31 on its inner end 32. The outer end 33 of member 30 has an upwardly inclined end 34 at an angle of about 90° and which is adapted to form a hook to receive the handle of a sadiron adapted to be hung there. A spring 35 has one end 36 fixed to the arm 16 and is provided with a curved lower end 37 bearing upon the upper face 38 of the bar 30. The said spring end 37 is adapted to drop into the groove 39 in said face 38 when the bar 30 is drawn outward its full extensible length to hold the bar 20 advanced until again pushed in against the tension of the spring. When the said bar is drawn out its terminal 34 is far enough beyond said end 22 to permit of hanging an iron 40 thereon, but when not in use, it is pushed in so that said terminal will be under the end 22 and thus out of the way. This provision of this gadget

2

will prevent the burning of ironing pads, clothes, etc., and also prevent the possibility of the iron sliding from the board and onto the foot of the user.

5 It is thought that persons skilled in the art to which the invention relates will be able to obtain a clear understanding of the invention after considering the description in connection with the drawings. Therefore, a more lengthy 10 description is regarded as unnecessary.

Changes in shape, size and rearrangement of details and parts such as come within the purview of the invention claimed may be resorted to, in actual practice, if desired.

15 Having now described my invention, that which I claim as new and desire to procure by Letters Patent is:

1. A flatiron holder comprising a U-shaped body member formed with oppositely disposed 20 parallel ends terminating in outwardly directed apertured attaching flanges, said ends having aligned rectangular bearing apertures formed therethrough, a flatiron supporting bar slidably disposed through said bearing apertures with one 25 surface thereof contacting the connecting portion of said body member, a hook on the outer end of said bar, means on the inner end of said bar for limiting the outward adjustment thereof, and means for automatically locking said bar 30 in extended position.

2. A flatiron holder comprising a U-shaped body member formed with oppositely disposed parallel ends terminating in outwardly directed apertured attaching flanges, said ends having 35 aligned rectangular bearing apertures formed therethrough, a flatiron supporting bar slidably disposed through said bearing apertures with one surface thereof contacting the connecting portion of said body member, a hook on the outer end of said bar, means on the inner end of said bar for limiting the outward adjustment thereof, means for automatically locking said bar in 40 extended position including a transverse locking groove formed in said bar, and a resilient arcuate locking finger on said body member automatically engageable in said groove when said rod is in extended position.

MARGARET MAY HOLLIDAY.
